TYPEWRITER CLAMP MEANS

John M. Roberts, Crystal Lake, Ill.

Application January 26, 1945, Serial No. 574,768

5 Claims. (Cl. 248—25)

1

This invention relates to improvements in typewriter clamp means and more particularly a clamp of this class which is adapted to hold the typewriter upon a slanting surface such as tiltable platform support of a desk which may in one position be concealed within the desk when the typewriter is not in use and elevated to horizontal position when the typewriter is being used. Also, when the typewriter is being used, the clamp assists in positioning the typewriter on the platform support and in minimizing objectionable movements of the typewriter on the support during use thereof.

It is an important object of this invention to provide an improved and simplified clamp of this type, which may be manufactured at relatively low cost and in quantity production, largely from thin section material, such as a metal stamping or suitable substitute therefor, while at the same time providing a device which may be applied in service with very little expenditure of time and effort and without any special knowledge being required.

The device of the present invention also permits typewriters to be removed from their usual tiltable platform supports, for cleaning, repairing, or exchanging, expeditiously and with a minimum of time and effort in doing so, and the device lends itself to ready adaptation to different makes of typewriters.

These and other objects and advantages will be apparent from the following description, taken together with the accompanying drawings, of an illustrative embodiment of the invention, and in which drawings—

Figure 1 is a perspective view of a desk and typewriter indicated generally and with the expedients of the present invention associated therewith;

Figure 2 is a perspective view of one of the clamps embodying the present invention;

Figure 3 is a plan view of the clamp of Figure 2 associated with the usual foot bar of a typewriter;

Figure 4 shows in full lines a longitudinal elevational view of the structure of Figure 3 with a fragmentary portion of the typewriter suggested by broken lines and also in dotted lines in Figure 4 is shown an alternative position of the typewriter platform support when the latter is tilted to be concealed, with the typewriter, within the desk;

Figure 5 is an enlarged fragmentary view, partly in section, taken on the line 5—5 of Figure 4; and

2

Figure 6 is a similar sectional view taken on the line 6—6 of Figure 4.

Referring in detail to the illustrative construction shown in the drawings, the numeral 10 indicates generally an office desk of the type having a central knee-hole 11 in which is mounted a plate-like typewriter platform support 12, which, when the typewriter, indicated generally by the numeral 13, is in use is horizontal within the knee-hole, and, when the typewriter is not in use, may be inclined downwardly, to be supported as by the diagonal cleats 14, with the typewriter 13, in slanting position thereon, and at this time the cover 15 being pulled upwardly and forwardly to lie horizontal in the plane of the desk top 16 and forming a continuation thereof over the knee-hole 11 to cover the typewriter.

The present invention has to do with means for clamping the typewriter 13 to the platform support 12 both when the support is horizontal and when it is tilted to inclined position, such as is indicated in dotted lines in Figure 4, such clamping means embodying the present invention being here exemplified by the pair of clamps 17 and 17a.

It may here be pointed out that one well known typewriter construction includes at each side of the typewriter and thereunder a foot bar 18 (Figs. 3 and 4) each of which carries a front foot 19 for the typewriter and a rear foot 20. In one common practice, the foot bar 18, of which it will be understood there are two, one at each side of the machine running from front to rear thereof, has a threaded socket 21 depending therefrom into which a screw-bolt (not shown) passing through a hole bored in the platform 12 passes upwardly to be threadedly received in the tapped recess 22 of the socket 21 to clamp the typewriter to the platform support 12. It is a purpose of the present invention to eliminate the necessity for the socket 21 and particularly the necessity for boring a hole in the platform support to take a clamping bolt therethrough. Such a hole mars the desk platform 12 and the installation is furthermore time consuming not only when originally made but more particularly when it is desired to clean, repair or exchange typewriters.

In accordance with the present invention, my improved clamping means is greatly simplified in construction and operation and one of these devices, represented by the numeral 17, is shown in perspective in Figure 2. It here includes a leg or foot engaging portion shown in the form of a frame 23 which is flat on its upper surface but having its rear edge turned down in a re-entrant bend as at 24 for enhanced rigidity,

Centrally of the frame is an opening 25, which in this instance is rectangular to receive the rectangular sub-foot 19a, which usually terminates at its lower end in an inverted suction cup 19b of rubber or the like which rests upon the desk platform 12 and supports the typewriter thereon, it being understood that the rear foot 20 comprises a similar sub-foot 20a and suction cup 20b and that each foot bar 18 carries two such feet. The machine screws 19c and 20c secure the feet 19 and 20, respectively, to the foot bar 18 securing at the same time the foot parts 19a and 19b, in one case, and the foot parts 20a and 20b in the other case, to the foot proper.

The opening 25 in the frame portion 23 of the clamp 17 is desirably of a size substantially just equal to the area of the lower face of the suction cup 19b so that the latter must be preferably forced into the opening 25, which however may be done by slight pressure, the rubber of the suction cup yielding for that purpose. The frame portion 23 then immediately underlies the foot bar 18 and margins the metal portion 19a of the sub-foot intermediate its height, the latter being narrowed to waist-like shape at this point in conventional practice.

At the outer side of the clamp 17, the frame portion 23 has downwardly struck flanges such as the inner flange 23a and outer flange 23b, both spaced laterally of the sub-foot 19a when the frame 23 is moved laterally outwardly to the limit of its movement on the sub-foot. Thereupon the frame portion 23 may be clamped to the foot 19 by a thumb-screw having a shank 26 and a winged head 27. The thumb-screw 26 passes freely through a perforation 28 in the outer flange 23b and is threadedly received in a tapped aperture 29 in the inner flange 23a. Screwing of the thumb-screw inwardly, which may be readily done manually by means of the wing head 27 of the thumb-screw, causes the inner end of the thumb-screw to press increasingly upon the sub-foot 19a and draws the frame portion 23 laterally thereon so that the margin of the frame advantageously becomes wedged in the narrow waist 30 between the foot 19 proper and its sub-foot 19a.

The connecting portion of the clamp in this instance includes a pair of telescoping box formations 31 and 32. The box formation 31 is advantageously a continuation of and integral with the frame portion 23, and this is shown as the inner of the two telescoping box formations here referred to. The outer said box formation 32 is, similarly, a continuation of and integral with the desk engaging or hook portion 33 of the clamp.

As best shown in Figure 6, these box formations telescope snugly but slidingly so that the distance between the hook portion 33 and the typewriter foot engaging portion on frame 23 may be increased or reduced as desired to suit different makes of typewriters, or to permit with the same make different distances of the typewriter keyboard from the edge 34 of the desk platform support. To fix such an adjusted length for the clamp, I provide securing means here represented by a lock pin 35 which has a shank 36 and a winged head 37. This locking pin passes freely through registering holes 38 and 39 in the outer lateral walls of the box formations 31 and 32 respectively, across the width of the box formations, freely through another registering hole 40 in the opposite wall of the inner box formation and screw threadedly into a tapped open-

ing 41 in the adjacent inner lateral wall of the outer box formation 32. Within the inner box formation is held a cushion-like body 42 desirably of sponge rubber or the like which fills the box formation 31 and has a reduced depending pad-like extension 43 which passes downwardly and outwardly through registering longitudinally elongated slots 44 and 45 in the lower faces respectively of the box formations 31 and 32 and contacts the upper surface of the platform support 12, thus elevating the metal parts of the clamp above the surface of the support 12 to avoid scratching the latter while permitting the typewriter foot 19b to pass through the frame 23 and also at the same time providing a friction member which grips the desk and minimizes movement of the clamp on the platform support, once the position of the typewriter is adjusted thereon, and to cooperate with the suction cups 19b on the typewriter feet to minimize movement of the typewriter on the platform support during use of the typewriter. It will be seen from Figure 6, that the shank 36 of the locking pin 35 passes freely through the rubber-like body 42, the latter being passaged as at 46 for this purpose.

As best seen from Figures 3 and 4, the holes for the locking pin 35 in the inner box formation 31 and the aligned passage through the rubber-like body 42 are multiplied in a number of places, in this instance five, spaced longitudinally along the inner box formation and which are here for convenience given the designating numeral 41. Thus, as in Figures 3 and 4, the clamp is shown contracted to its limit in this direction, the locking pin 35 being in the passage 41 nearest the frame portion 23 of the clamp. If it be desired to extend the clamp, the locking pin 35 may be temporarily removed by manually unscrewing the pin, the fingers of the operator readily engaging the winged head 37 for this purpose, then decreasing the overlap of the box formations 31 and 32 until one of the other passages 41 in the inner box formation 31 registers with the holes 39 and 41 in the outer box formation upon which the locking pin 35 may be replaced and again threadedly screwed into the tapped hole 41.

Turning finally to the desk engaging portion 33 of the clamp, this is shown in the form of a hook, and, as best seen in Figures 1 and 4, takes about the outer edge 34 of the platform support 12, the hook portion being preferably of a configuration which its designation signifies, namely of semi-cylindrical shape receiving therewithin the edge 34 of the platform support and conforming somewhat thereto. On its inner surface it is desirably faced with a buffer or layer of soft material 48 such as felt to prevent scratching of the desk. Its exterior face is advantageously arcuately ribbed as at 49 for enhanced strength. As shown in the drawings, the hook has an arcuate height materially of greater dimension vertically than the thickness of the platform 12 and the hook engages the platform only at the lower surface of the platform, this being assured by the cushion-like member 43 which elevates both the frame 23 and the hook 33 above the platform.

It will now be understood that in practice there will be two of the clamps, such as 17 and 17a, used with the typewriter 13 on the platform support 12, one below each side of the typewriter, the one shown in Figure 2 being preferably the right-hand clamp as seen in Figure 1 so that the thumb screws 27 and 37 are accessible to the

fingers of the operator at that side of the typewriter. The companion clamp 17a at the left-hand side of the typewriter 13 is desirably formed similar to the clamp 17 except that the depending flanges 23a and 23b are located on the left-hand margin of the frame portion 22 instead of the right-hand margin as shown in Figure 2. Similarly, the thumb screw 37 or in other words the lock pin 35 will enter from the left-hand lateral wall of the box formation 32 and will pass to the right through the inner box formation and threaded into the hole 39 of the outer box formation. Thus, the clamps 17 and 17a are in pairs which are symmetrical though not identical, like the human hands, and serve somewhat as mechanical hands which retain the typewriter in position both when the platform support 12 is horizontal as shown in Figure 1, when the typewriter is being used, and also when the platform support is tilted downwardly as shown in dotted lines in Figure 4, when the typewriter is not in use and is concealed on the platform support within the desk, the cover 15 being then pulled upwardly and forwardly to lie horizontal in the desk and cover the typewriter.

It is to be understood that the invention is not intended to be limited to details of construction shown for purposes of exemplification and that such changes may be made as fall within the scope of the appended claims without departing therefrom.

The invention having been described, what is here claimed is:

1. In a clamp device of the class described, the combination of typewriter engaging means for detachably engaging a leg of the typewriter while the typewriter foot rests upon the desk, desk engaging means extending forwardly of said leg engaging means and for engaging the front edge of a desk portion, an adjustable connecting portion between said means, and cushion-like friction means carried by said connecting portion and arranged to support the connecting portion on the desk.

2. In a typewriter clamp device, the combination of a typewriter engaging means for detachably engaging a leg of the typewriter while the typewriter foot rests on the desk, desk engaging means extending forwardly of each leg engaging means and for engaging the front edge of a desk, an adjustable connecting portion between said means, and non-metallic friction means carried by said connecting portion and arranged to support the connecting portion on the desk, wherein the first mentioned means is of frame formation and has a central opening to receive a typewriter foot therethrough to rest upon the desk, and wherein releasable clamping means are carried by the device for engaging the typewriter foot when in said frame, and wherein said releasable clamping means includes a manually operable screw for engaging said foot.

3. In a typewriter clamp device, the combination of typewriter engaging means for detachably

engaging a leg of the typewriter while the typewriter foot rests on the desk, desk engaging means extending forwardly of each leg engaging means and for engaging the front edge of a desk, an adjustable connecting portion between said means, and non-metallic friction means carried by said connecting portion and arranged to support the connecting portion on the desk, wherein said connecting portion is of telescoping box formations and comprises a rubber-like body within said formations and having a pad portion depending through registering openings in the lower walls of said box formations to engage the desk.

4. Means for removably clamping a typewriter to a plate-like platform, comprising a pair of clamp members each embodying a typewriter engaging part for engaging a front foot of the typewriter intermediate of the height of the foot, a platform engaging part for hooking about the front edge of the platform and having its upper part spaced upwardly from the platform upper surface, and a connecting portion between said typewriter engaging part and said platform engaging part, said connecting portion including a cushion-like element for resting on the platform and serving to elevate both the typewriter engaging part and the upper part of the platform engaging part above the platform whereby each clamp member engages the upper surface of the platform only through the intermediation of the cushion-like element to avoid scratching the said surface, each said clamp member being extensible to accommodate the position of the typewriter feet spaced from the front edge of the platform.

5. Means for removably clamping a typewriter to a desk or the like, embodying a typewriter engaging part comprising an open frame somewhat snugly receiving the typewriter foot therethrough to rest upon the desk, a desk engaging part adapted to hook about the front edge of the desk, and a connecting portion between said typewriter engaging part and said desk engaging part, said connecting portion including a cushion-like element adapted to rest on the desk and serving to elevate the typewriter engaging part above the desk whereby to permit the foot to pass therethrough while being engaged intermediate of its height.
